UNITED STATES PATENT OFFICE

JEROME MAIBAUM, OF NEW YORK, N. Y.

ELECTRICAL CONDUCTOR

Application filed February 2, 1929. Serial No. 337,053.

This invention relates to improvements in electrical cords.

It is an object of this invention to provide electrical cords which are non-kinking in ordinary use, and in which the provision of means for preventing kinking does not materially lessen the desired flexibility of the cords.

For convenience in description the word "cord" is used to include any small cable, either single or multi-conductor, which is very flexible and is substantially insulated to withstand wear.

In the accompanying drawings and description which disclose an embodiment of the invention selected for purposes of illustration:

Fig. 1 is a plan view of a short section of a cord having the several parts thereof progressively removed to show the interior construction;

Fig. 2 is a greatly enlarged view generally similar to Fig. 1, showing the construction of the cord in more detail; and

Fig. 3 is a cross-section on the line 3—3 of Fig. 2.

Cords heretofore known and used for forming a flexible electrical connection between an electrical appliance or apparatus and another electrical appliance or apparatus, or an electrical system, have not been entirely satisfactory because of the inherent tendency of the cords to kink or twist up.

This tendency of the cords to kink is particularly pronounced in very flexible cords, for example, in lamp cords, and in cords of the general type ordinarily used for connecting a telephone receiver to a telephone instrument. In cords of this nature the electrical conductors usually are made up of a plurality of fine wires or of tinsel which may be braided or twisted together. These conductors are enclosed in separate insulating sheaths, and one or more of the insulated conductors are enclosed within, and if a plu-

rality, are bound together by, an outer jacket which usually is of braided fabric.

The invention disclosed herein provides a non-kinking cord without materially lessening the desired flexibility of the cord, and without materially increasing the overall dimensions of the cord.

For purposes of illustration the invention has been shown in connection with a two conductor cord. It will be apparent, however, that the invention is applicable to any cord, whether having one, two or more conductors.

Referring to Fig. 1, there is shown a section of flexible two conductor cord, the outer jacket 10, suitable means 11 for preventing kinking, and the separate insulating sheaths 12 and 13 being progressively cut away from the conductors 14 and 15 to show the construction.

As may better be seen in Fig. 2, which is a greatly enlarged view similar to Fig. 1, the two electrical conductors 14 and 15 are provided with separate insulating sheaths. Ordinarily the conductors will consist of a plurality of fine wires or of tinsel, either braided, or twisted together as shown. The separate insulating sheaths for the conductors may be of any approved type. In the embodiment of the invention disclosed herein, the conductors 14 and 15 are encased in insulating sheaths 12' and 13', respectively, for example of rubber. Overlying the rubber sheaths 12' and 13' are the braided fabric jackets 12 and 13.

Extending along the insulated conductors which are assembled in parallel relationship is a strip of flexible material 11, preferably overlying a filler space formed between the conductors. Preferably the strip 11 is made of paper, and it may be a single layer or it may be laminated to provide the requisite stiffness. If desired, a similar strip 16 may also extend along the conductors, overlying the other filler space.

The assembled conductors and strips are enclosed in the outer jacket 10, which preferably will be the customary braided fabric cover. The strips 11 and 16 conveniently 5 may be drawn into place along the insulated conductors, for example, off of supply rolls, coincidently with the braiding on of the outer jacket 10. While other means may be provided for maintaining these strips in position 10 overlying the filler spaces between the conductors, ordinarily the pressure of the outer jacket 10 will be sufficient to maintain them in place.

The effect of the strip 11, or of the strips 15 11 and 16 is to tend to give the cord a certain degree of rigidity in the plane parallel to the flat surfaces of the strips, but without materially affecting the flexibility of the cord in the plane at right angles to the first plane. 20 This added rigidity from the strip or strips is so slight that it in no way interferes with the desired overall flexibility of the cord, but it is sufficient to prevent undesirable kinking and twisting of the cord under normal use. 25

While the drawing discloses each of the 30 filler spaces having an overlying strip, ordinarily it will be sufficient to so provide only one of the filler spaces. In cords having more than two conductors, one or all, or any intermediate number of the filler spaces may be 35 provided with the overlying strips in a similar manner.

It may be found desirable to corrugate the 35 paper strips, either laterally or longitudinally, or to provide them with shallow indentations for the purpose of adding lateral 40 rigidity.

The invention may be variously modified 45 and embodied within the scope of the subjoined claims.

I claim:

1. An article of manufacture comprising, 45 in combination, a plurality of flexible metallic conductors, separate insulating sheaths surrounding each of said conductors, an outer jacket surrounding and binding said conductors together in parallel relation, and a thin flat strip enclosed within said outer jacket and extending along parallel to and bridging a filler space between said conductors for preventing kinking of the article. 50

2. An article of manufacture comprising, 55 in combination, two metallic conductors, separate insulating sheaths surrounding each of said conductors, an outer fabric jacket surrounding and binding said conductors together in parallel relation, and a thin flat strip of fibrous material enclosed within said outer jacket and extending along parallel and tangent to said insulated conductors for preventing kinking of the article. 60

3. An article of manufacture comprising, 65 in combination, two parallel, flexible electrical conductors, separate insulating sheaths

surrounding each of said conductors, an outer braided jacket surrounding and binding together said conductors, and flat strips of flexible material of a width substantially equal to the distance between conductor centers enclosed within said braided jacket and extending along said conductors overlying the filler spaces between the insulated conductors for preventing kinking of the article. 70

In testimony whereof, I have signed my name to this specification this 29th day of January, 1929.

JEROME MAIBAUM.
